UNITED STATES PATENT OFFICE.

ARTHUR J. BASTIAN, OF WILKINSBURG, PENNSYLVANIA, ASSIGNOR TO WESTINGHOUSE ELECTRIC & MANUFACTURING COMPANY, A CORPORATION OF PENNSYLVANIA.

TIMING DEVICE.

Application filed April 23, 1920. Serial No. 375,992.

To all whom it may concern:

Be it known that I, ARTHUR J. BASTIAN, a citizen of the United States, and a resident of Wilkinsburg, in the county of Allegheny and State of Pennsylvania, have invented a new and useful Improvement in Timing Devices, of which the following is a specification.

My invention relates to time-measuring devices, and particularly to electrically controlled means for giving a signal, when a machine has been in operation for a predetermined period of time.

One object of my invention is to provide a device of the above indicated character that shall indicate to a workman that his machine, such, for example, as a hot-press, has operated for a required period of time.

Another object of my invention is to provide comparatively simple and inexpensive means, having great durability and efficiency, for operating a number of such devices, whereby a workman who is in charge of a plurality of machines may be warned when each machine has been in operation for a predetermined period of time.

Heretofore, it has been customary to provide devices for the same purpose with a motor for each, thereby making the cost of installation more expensive and the cost of maintenance relatively greater.

I have provided a single motor, which operates a plurality of timing devices. The parts of each device are readily accessible and are so simple in design that little skill is required by a workman to operate and repair them. Each device rings a bell to attract the workman's attention to the machine and energizes an electric lamp to indicate which of the machines has been in operation the required period of time.

Reference may now be had to the accompanying drawings, Fig. 1 of which is a view, in end elevation, of a timing device embodying my invention mounted on a hot-press and driven by an electric motor. Fig. 2 is a view, in side elevation, of the timing device and the hot-press shown in Fig. 1. Fig. 3 is a view, in end elevation, of a simi-

lar timing device mounted on a hot-press and driven by a shaft, which is operated by a motor some distance therefrom. Fig. 4 is a view, partly in side elevation and partly in section, of the timing device shown in Figs. 1 and 2. Fig. 5 is a view, partially in end elevation and partially in section, of the timing device shown in Fig. 4. Fig. 6 is a view, in side elevation, of a rocker shown in Figs. 4 and 5. Fig. 7 is a view, in end elevation, of the same. Figs. 8 and 9 are views, in side and in end elevation, respectively, of a shifting pin shown in Fig. 4.

Referring particularly to Figs. 1 and 2, a timing device 1 embodying my invention is shown securely mounted on a hot-press 2 and is connected to a synchronous motor 3 by a gearing 4 and a shaft 5. A bar or lever 6, attached to a movable base portion 7 of the hot-press 2, engages an arm 8 of a timing device 1. The motor 3 is mounted on a bracket 9 which is attached to the hot-press 2. An electric lamp 10 and a bell 11 are provided for producing signals by the timing device 1.

The gearing 4 comprises a pinion 12 that is mounted on the shaft of the motor 3, a gear wheel 13, a worm screw 14, a worm wheel 15, a worm screw 16, a worm wheel 17, and a shaft 18. A gear wheel 19, mounted upon the shaft 18, engages a gear wheel 20 mounted upon the shaft 5.

In Fig. 3, the timing device 1 is mounted on a hot-press 2 and is driven by a shaft 5 which operates a plurality of similar devices. The shaft 5 is provided with a plurality of universal joints 21 to provide for the timing devices being slightly out of alignment, and it is driven by the motor 3.

Referring to Figs. 4 and 5, the timing device 1, which is also shown in Figs. 1 and 2, comprises a case 22, made of some suitable rigid material, such, for example, as wood, metal or micarta; the shaft 5 and a circular dial plate 23 fixedly mounted thereon by means of annular discs 24 and 25, screws 26 and a taper pin 27. A face plate 28, graduated with even numbers between zero and 120, and having a circular opening in which

the dial plate 23 rotates, is attached to the case 22.

An arm or pointer 29, provided with a pin 30 and a spring 30a, is rotatably mounted 5 upon the shaft 5 and the disc 25, and it may be actuated by the dial plate 23 by causing the pin 30 to engage one of the sixty holes punched therein. These holes are equidistant from the center of the dial plate 23 and 10 are uniformly spaced with respect to each other.

A bar or knocker 31 is pivotally mounted upon a pin 32 and engages a rocker 33, which is pivotally mounted upon a pin 33a. 15 The movement of the bar 31 is limited by posts 34 and 35. A hammer 36 is secured to the rocker 33 by a bent arm 36a (see Figs. 6 and 7 of the drawings) and, when the rocker is actuated clockwise, it strikes the 20 bell 11. A copper brush 37, attached to the rocker 33, engages a post 38 when the rocker is rotated clockwise and completes an electric circuit which comprises the electric lamp 10, rocker 33 and binding posts 34 and 38. 25 Rapid movement of the rocker 33 is obtained by the manner in which its angular projection 39 engages a projection 40 of a shifting pin 41 (see Figs. 8 and 9 of the drawings). The shifting pin 41 is provided with a helical spring 42a that maintains in contact relation the two projections 39 and 40 of the rocker 33 and the shifting pin 41, respectively. The rocker 33 is provided with two 30 projections 42 and 43 between which some free movement is permitted the knocker 31. The outward movement of the knocker 31 is 35 resiliently resisted by a pin 44 provided with a helical spring 45.

The arm 8 of the rocker 33 is so bent 40 that it may be engaged by plate 45' that is attached to a bar 46. The arm 8 may assume positions 8a, 8b, and 8c, in accordance with the manner in which the projection 39 of the rocker 33 engages the projection 40 of the shifting pin 41.

The bar 46 is pivotally mounted in a bracket 47 of the lever 6. A rod 48, provided with a helical spring 49, is resiliently mounted in a bracket 50, forming part of the 50 lever 6, and is attached to the bar 46.

Figs. 6 and 7 are views, in side and in end elevation, respectively, of the rocker 33. An angle of 70° is formed by the two intersecting faces of the projection 39.

Figs. 8 and 9 are views in side and in end elevation, respectively, of the shifting pin 41 and its projection 40. The two faces of the projection 40 intersect at an angle of 90°.

When a plurality of hot-presses are started 60 in operation, it is necessary that a warning be given when various periods of time have elapsed, depending upon the work to be performed by each machine. To obtain this, the motor 3 is started, which causes the shaft

5, the dial plate 23 and arm 29 of each timing device 1 to turn in a clockwise direction once in two hours.

The operator, having placed an object, such, for example, as a commutator, on one of the hot-presses, and desiring that it be in the machine for thirty minutes, moves the pointer 29 to the graduation 30 marked upon the face plate 28. The pointer 29 begins to rotate in a clockwise direction and, 75 in thirty minutes thereafter, will return to the zero graduation.

When the operator raises the base portion 7 of the hot-press 2, the lever 6, which is attached thereto, rises with it, and the plate 45' engages the arm 8 of the rocker 33 and thereby causes it to move inwardly to position 8a. The rotation of the rocker 33 to the left removes the hammer 36 a slight distance from the bell 11.

When the pointer 29 rotates to zero, the knocker 31 is forced outwardly and it, in turn, by engaging the projection 42 of the rocker 33, causes the rocker to assume position 8b which is that shown in the drawing. 90 A relatively slight movement beyond this position results in the projection 39 rotating beyond projection 40 of the shifting pin 41, and the spring 42a forces the pin 41 downwardly, thereby causing an accelerated movement of the rocker to position 8c. In this position, the bell 11 is struck by the hammer 36, the copper brush 37 engages the posts 38 and the projection 42 engages the post 34.

In the above position of the rocker 33, the electric lamp 10 is energized by the completion of a circuit comprising the rocker 33, copper brush 37, binding posts 34 and 38, and the electric lamp 10. The electric lamp will continue to burn as long as the rocker 33 is in the position 8c.

By having the bar 46 pivotally mounted on the lever 6, the pin 8 of the rocker 33 will not be damaged, if it fails to move when engaged by the plate 45'.

The operations that have been previously described are repeated each time an article is baked in a machine. The only operations that are required are to reset the pointer 29 115 and to place the article properly in the machine. The device is so designed that it is immaterial what angular position the dial plate 23 occupies, as the graduations are marked upon the stationary face plate 28.

If it is desired to inspect the interior of a timing device, the face plate 28 may readily be detached from the case 2.

From the above description it may be seen that the chief advantages of my invention are that a single motor may operate a plurality of timing devices and that the signals are such as to insure notice to the workman that the desired time of operation of the machine has expired, and the electric 125

light prevents the workman from selecting the wrong machine.

While I have shown my invention in a preferred form, it may be subjected to slight modifications, and, therefore, I desire to be limited only by the scope of the appended claims.

I claim as my invention:

1. In a timing device, the combination 10 with a bell, a shaft and means comprising a motor for driving said shaft at a uniform speed, of an arm turned by said shaft, an electric circuit comprising a lamp, and mechanical means actuated by said arm for 15 ringing said bell and for opening and closing said circuit.
2. In a timing device, the combination 20 with a shaft and means for driving said shaft at a uniform speed, of a dial securely mounted upon said shaft and rotated thereby, an arm rotatably mounted upon said shaft, a movable pin for mechanically connecting said arm to said dial, and means actuated by said pin for giving a signal 25 when said arm has turned through a predetermined angle.
3. In a timing device, the combination 30 with a shaft and means for driving said shaft at a uniform speed, of a dial securely mounted upon said shaft and rotated thereby, an arm rotatably mounted upon said shaft which may be actuated by said dial, a pivotally mounted bar that is actuated by said arm, a resilient member for returning 35 said bar to a predetermined position when it is not engaged by said arm, a rocker having projections and actuated by said bar, a bell that is struck by a projection of said rocker, a resilient member for moving said 40 rocker with great rapidity, and an arm for returning said rocker to a predetermined position.
4. In a bell ringing device, the combination 45 with a bell, of a pivotally mounted rocker having projections, one of which strikes said bell when said rocker is actuated, a resilient member so engaging one of the projections of said rocker that the movement of the rocker occurs with relatively 50 great rapidity, a pivotally mounted bar actuating said rocker, means for actuating said bar, means for limiting the forward and the reverse movement of said rocker and said bar, and means for returning said rocker to 55 its initial position after ringing said bell.
5. In a timing device, the combination 60 with a machine and an independently operable member, of a signal device, a plurality of relatively adjustable co-operating indicating members movable in concert in response to movement of said independently operable member for actuating the signal device, and means responsive to a movement of said machine for controlling the 65 signal device.
6. The combination with a plurality of independently operable machines, of means for indicating the duration of operation of each machine comprising a signal device for each machine, a single movable actuating 70 means, a plurality of relatively adjustable co-operating indicating members responsive to said actuating means for actuating each signal device, and means responsive to a movement of each of said machines for controlling the signal device thereof. 75
7. The combination with a plurality of machines, of means for indicating the duration of operation of each machine, and a single means flexibly connected to the machines for actuating the indicating means and compensating for differences in the relative positions of the machines. 80
8. In a timing device, the combination with 85 a plurality of signal devices, means for actuating the same, and means for moving the actuating means at a uniform speed, of a member moved by said actuating means, an electric circuit connected to one of said signal devices, and means actuated by said member for mechanically operating another of said signal devices and controlling said circuit. 90
9. In a timing device, the combination 95 with an actuating member and means for moving the same at a uniform speed, of an indicating member secured to the actuating member, a second indicating member relatively movably mounted on the actuating member, adjusting means for securing said indicating members in fixed relative position on the actuating member, and means responsive to simultaneous movement of said indicating members for giving a signal 100 when said actuating member has moved a predetermined amount. 105
10. In a timing device, the combination 110 with a shaft, and means for driving said shaft, of a dial securely mounted on said shaft and rotated thereby, an arm relatively movably mounted upon said shaft and adapted to be actuated by said dial to move in concert with the shaft, means actuated by said arm for giving a signal when said arm has turned through a predetermined angle, and stationary means adjacent to said dial for determining arcuate distances upon said dial. 115
11. In a timing device, the combination 120 with a plurality of machines and a synchronous motor, of means operated by said motor for signalling when each machine has operated for a predetermined period of time, and means attached to each machine for resetting a portion of said means when said machine begins a new operation. 125
12. In a timing device, the combination 130 with a plurality of machines and a constant-speed motor, of signalling means associated with each machine, means whereby the mo-

tor actuates all of the signalling means, and means responsive to a movement of each machine for controlling the signalling means thereof.

5. 13. In a timing device, the combination with a dial, of means for actuating said dial at a constant speed, a stationary face plate provided with a plurality of graduations

for measuring arcuate distances upon said dial, and signalling means operable upon said dial turning through a predetermined angle. ¹⁰

In testimony whereof, I have hereunto subscribed my name this 12th day of April 1920.

ARTHUR J. BASTIAN.
